UNITED STATES PATENT OFFICE.

GEORGE F. CONNER, OF PORT HURON, MICHIGAN.

DESIGN FOR A TOOTH FOR THRESHING-MACHINE CYLINDERS.

SPECIFICATION forming part of Design No. 32,400, dated March 27, 1900.

Application filed March 1, 1900. Serial No. 7,020. Term of patent 14 years.

To all whom it may concern:

Be it known that I, GEORGE F. CONNER, a citizen of the United States, residing at Port Huron, in the county of St. Clair and State of Michigan, have invented and produced a new and original Design for Teeth for Threshing-Machines, of which the following is a specification, reference being had to the accompanying drawings, forming a part thereof.

10 This invention relates to a new and original design for teeth for threshing-machine cylinders, and it is embodied in the form and configuration of tooth presently to be described, and illustrated in the accompanying drawings.

15 In the drawings, Figure 1 is a side elevation of the tooth. Fig. 2 is an edge view, and Fig. 3 is a top plan view.

The tooth or casting has a shank portion A, 20 formed with flat sides, and a slightly-curved back side *a*.

B designates a blade portion slightly tapered, having flat sides with a slightly-curved rear edge, the curvature of which forms a continuation of the curved rear side *a* of the 25 shank. The entire back of the tooth is slightly convexed transversely. The blade portion B,

as stated, is slightly tapered, and its lower end is broadened and is slightly rounded on the toe, as at *b*. The front face of the tooth, including the shank and blade, is substantially concaved and is curved transversely in opposite directions rearward, forming a convexed edge—that is to say, the front face of the tooth is longitudinally concaved and transversely convexed.

The essential feature of the design is the particular shape of the tooth, having a transversely - convexed and longitudinally - concaved forward edge and curved rear edge, substantially as shown.

Having thus described my invention, what I claim as new, and desire to secure by Letters Patent, is—

The design for a tooth for a threshing-machine cylinder, substantially as shown and described.

In testimony whereof I have affixed my signature in presence of two witnesses.

GEORGE F. CONNER.
